(57) **CLAIM**

The ornamental design for a kitchen grip mitt, substantially as shown and described.

DESCRIPTION

FIG. 1 is a front elevational view of a kitchen grip mitt showing my new design therefor;

FIG. 2 is a side-elevational view thereof with the opposite side being a mirror image thereof;

FIG. 3 is a top plan view thereof;

FIG. 4 is a bottom view thereof; and,

FIG. 5 is a rear elevational view thereof.

The fragmentary cross-hatch pattern shown in the drawing is understood to represent fabric and is repeated uniformly throughout the areas shown.

The broken lines shown in the drawing are understood to represent stitching.
